UNITED STATES PATENT OFFICE.

LAROY S. STARRETT, OF ATHOL, MASSACHUSETTS.

DESIGN FOR A TRY-SQUARE.

SPECIFICATION forming part of Design No. 24,503, dated July 23, 1895.

Application filed May 20, 1895. Serial No. 549,998. Term of patent 14 years.

To all whom it may concern:

Be it known that I, LAROY S. STARRETT, of Athol, in the county of Worcester and State of Massachusetts, have invented and produced a new and original Design for Try-Squares, of which the following, taken in connection with the accompanying drawings, is a specification.

My design is peculiar in that the rectangular stock or body A of the tool has a smooth raised border or marginal portion a and a sunken interior portion scored or roughened uniformly and having in its lower half an opening B through it, while its upper half has extending from the end wall or border a smooth semi cylindrical or convex protuberance C extending centrally about parallel with the side walls or edges and terminating in a cylindrical cap D, occupying a recess in the body or stock and having two or more perforations in it. A graduated blade E extends at a right angle from the upper end of said body in a manner common in such tools.

In the drawings, Figure 1 is a side view showing the complete design, and Figs. 2 and 3 are sections on the dotted lines 2 2 and 3 3, ²⁵ respectively, showing the raised and sunken portions.

The mechanical features of my invention are set forth in an application of that character filed simultaneously herewith, Serial No. ³⁰ 549,924.

I claim as my invention—

The design for a try-square substantially as herein shown and described.

In testimony whereof I have signed my ³⁵ name to this specification, in the presence of two subscribing witnesses, on this 22d day of April, A. D. 1895.

LAROY S. STARRETT.
